UNITED STATES PATENT OFFICE.

HENRY M. HALLETT, OF LUDINGTON, MICHIGAN

SMOKING-PIPE.

No. 874,332.

Specification of Letters Patent.

Patented Dec. 17, 1907.

Application filed January 17, 1907. Serial No. 352,748.

To all whom it may concern:

Be it known that I, HENRY M. HALLETT, of Ludington, in the county of Mason and State of Michigan, have invented certain new and useful Improvements in Smoking-Pipes; and I do hereby declare the following to be a full, clear, and exact description of the invention, such as will enable others skilled in the art to which it appertains to make and 10 use the same.

The object of this invention is to provide an attachment for tobacco pipes for effecting the drying or evaporation of nicotin, saliva, and other moistures which usually accumulate 15 late in pipe bowls; and also to allow the smoke to pass freely from the pipe bowl without coming into contact with saliva and other moistures so disagreeable to smokers.

The invention will be hereinafter fully set 20 forth and particularly pointed out in the claims.

In the accompanying drawings, Figure 1 is a vertical sectional view of a pipe embodying my improvement. Fig. 2 is a view of 25 the attachment removed. Fig. 3 is a face view of the tobacco rest. Fig. 4 is a view of the lower portion of the attachment. Fig. 5 is a cross sectional view on line 5—5, Fig. 1.

Referring to the drawings, the attachment 30 comprises a plate 1 constituting the rest or support for the tobacco load, and a cup 2 secured to and depending from the underside of such plate, both being located in the bottom of the bowl, a circumferential space, 35 however, being left between the cup and the surrounding wall of the bowl. These two parts are united by a nutted screw 3, the head of which rests on the top of plate 1, while the nut 4 bears against the bottom of 40 the cup. This screw is surrounded by an asbestos sleeve 5. In plate 1 I form a series of openings 6 by striking up the metal from the underside thereof, such openings permitting the smoke to pass freely, while the projecting walls prevent ashes, nicotin, and other objectionable substances from reaching 45 the bottom of the bowl. This plate becomes very much heated, when in use, and the heat so given off is intended to effect the 50 drying or evaporation of the nicotin or oils of tobacco. The cup is also formed with a series of smoke-outlet openings 7 formed by the metal being struck up from the interior of the cup, the walls projecting outwardly 55 and downwardly so that saliva or other moistures are prevented from entering and

befouling the cup chamber. The heat of the burning tobacco is transmitted through the nutted screw 3 to the underside of the cup, and such heat is intended to dry or evaporate 60 any saliva which may reach the bowl through the stem. The asbestos sleeve 5 serves to prevent the heat conducted by the screw 3 being given off before it reaches the under- 65 face of cup 2.

In practice, the outer edge of plate 1 is slightly turned upward when the device is pressed tightly into the pipe bowl, thereby preventing ashes, nicotin, or particles of tobacco from passing between the device and 70 the inside of the bowl. As stated before, such substances are likewise prevented from passing through the protected openings in the top plate 1, although free passage is allowed for the smoke. By means of my improvement all moisture flowing through the pipe stem into the bowl is quickly dried or 75 evaporated.

A device of the character described is extremely simple and inexpensive, and may be 80 readily replaced, at but slight cost, when conditions require.

I claim as my invention:

1. The combination with a pipe, of an attachment designed to fit in the bowl thereof, comprising a plate forming a rest or support for the tobacco load having a series of smoke outlets, a cup depending from said plate through which the smoke must pass in its outward travel, a screw uniting said cup to 85 said plate and designed to transmit the heat of the latter to the underside of said cup, and a non-heat conductor surrounding said screw within said cup.

2. The combination with a pipe, of an attachment designed to fit in the bowl thereof, comprising a plate having a series of smoke outlet openings, means extending upwardly from such plate surrounding said openings to prevent ashes, nicotin, etc. from passing 90 therethrough, a cup depending from the underside of said plate, with a circumferential space between it and the pipe bowl, said cup also having smoke outlet openings, and means protecting such openings for preventing 100 saliva from entering said cup.

3. The combination with a pipe, of an attachment designed to fit in the bowl thereof, comprising a metallic plate having a series of smoke outlet openings formed by striking up 110 the metal, the edges of the latter around said openings preventing ashes, nicotin, etc.

from passing therethrough, a metallic cup depending from the underside of said plate, with a circumferential space between it and the pipe bowl, said cup also having smoke 5 outlet openings formed by striking up the metal, the edges of the latter preventing saliva from entering said cup.

4. The combination with a pipe, of an attachment designed to fit in the bowl thereof, 10 comprising a plate having a series of smoke outlets formed therein by openings struck up from the underside thereof, a cup depending from said plate having a series of smoke outlet openings formed by being struck up from

the underside thereof, a circumferential 15 space being left between said cup and the wall of the bowl, a screw connecting said cup to said plate, the heat of the latter being designed to be transmitted through said screw to the underside of the cup, and an asbestos 20 sleeve surrounding said screw within the cup.

In testimony whereof, I have signed this specification in the presence of two subscribing witnesses.

HENRY M. HALLETT.
